UNITED STATES PATENT OFFICE.

WILLIAM B. STRATTON, OF DETROIT, MICHIGAN.

LAVATORY FIXTURE.

1,417,583.

Specification of Letters Patent. Patented May 30, 1922.

Application filed August 27, 1921. Serial No. 495,924.

To all whom it may concern:

Be it known that I, WILLIAM B. STRATTON, a citizen of the United States of America, residing at Detroit, in the county of Wayne and State of Michigan, have invented certain new and useful Improvements in Lavatory Fixtures, of which the following is a specification, reference being had therein to the accompanying drawings.

- 10 The invention relates to fixtures designed for use in connection with lavatories or bath tubs and has for its object: first, avoidance of a splashing of the water when discharged into the bowl; second, provision for thoroughly commingling hot and cold water before discharge so as to secure any desired temperature. To this end the invention consists in the construction as hereinafter set forth.
- 20 In the drawings:
- Figure 1 is a vertical central section;
- Figure 2 is a perspective view of a modified construction;
- Figure 3 is a plan view of said modification;

Figures 4 and 5 are vertical sectional views of the same taken respectively on lines 7-7 and 8-8 of Figure 3.

A is the bowl or other receptacle into which the water is to be discharged, said bowl having a marginal rim A'. B is an auxiliary receptacle or water chamber, so arranged that it will overflow into the receptacle A. As specifically shown, the receptacle B is arranged at the rear of the bowl and rises to a height slightly above that of the rim A', being provided with a discharge lip B' overhanging the bowl. Said receptacle is of a cylindrical form and is provided with a detachable bottom formed by plug B² screw threaded into the cylindrical body. The rim of the bowl A is formed with an aperture C, into which the receptacle B is inserted, said receptacle being formed with an annular shoulder D which supports the receptacle through engagement with the basin marginally of said opening. Below the rim C the receptacle is externally screw threaded for engagement by a nut E which clamps against the under face of the rim to hold the receptacle rigid therewith.

The lower portion of the receptacle has communication with a laterally projecting fitting F having hot and cold water pipes G and H respectively communicating with

its top and bottom. Within the fitting F are formed upper and lower chambers G' and H' within which are respectively located slide valves I for controlling the flow of hot and cold water. Said valves are adapted to be controlled in common by a vertical stem J disposed within the receptacle B, and rotatable in the bearing K formed integral with the upper portion of said receptacle, 65 said stem being surmounted by an operating handle L. Coiled springs M urge the valves I into normal engagement with tapering seats N suitably provided within the fitting F. To accomplish unseating of the valves 70 a pair of cams O and O' is mounted upon the lower portion of the stem J to bear against heads P terminally carried by the stems P' of the valves I. Said cams are so shaped and arranged as to successively act 75 upon the two valves. The valves I respectively slide in tubular casings Q which are inclosed within and spaced from cylindrical strainers R formed with slots for the passage of the water. The casings Q are respectively 80 formed with spiral series of orifices S which are successively uncovered as the valves are unseated, permitting an extensive graduation of the flow.

In the use of the described device, when 85 the stem J is actuated in the direction indicated by the arrow in Figure 4, the cold water controlling valve is first gradually unseated by the cam O. The cam O' then takes effect upon the hot water controlling valve 90 gradually unseating the same so that the proportion of hot water mixed with the cold is gradually increased until the hot and cold water are discharged in an equal quantity. Continued rotation of the valve stem in 95 the same direction cuts off the flow of cold water gradually until the flow consists entirely of hot water. A still further rotation gradually reduces the flow of hot water until eventually the same is cut off entirely. Thus it is seen that either hot or cold water, or a mixture of the same, in regulable proportions is obtained through the use of the described valve mechanism, said water discharging from the fitting F into the lower 100 portion of the receptacle B filling said receptacle and finally overflowing by way of the lip B' into the basin A. The velocity of the discharging stream is checked in the receptacle B, and since the water will merely 105 rise in said receptacle and overflow by gravity, excessive splashing is avoided; and fur-

thermore the hot and cold water are thoroughly commingled before reaching the point of overflow from said receptacle.

In the modified construction illustrated in Figures 2 to 5 inclusive, the receptacle T is of a rectangular shape and is engaged with the rim portion of the bowl similarly to the first described construction. In the modification, however, the two valves U and U' controlling respectively the flow through the hot and cold water pipes V and V' are arranged below the receptacle T, and are separately controlled by valve stems W surmounted above the receptacle by handles W', said stems engaging bearings X formed externally upon opposite sides of the receptacle. Beyond the valves U and U' said pipes V and V' discharge into a common pipe Y which opens into the lower portion 20 of the receptacle T. This form of the invention possesses substantially the same advantages as have been already enumerated, except that there is no automatic proportioning of the flow of the hot or cold water, 25 the control of the two valves being independent.

What I claim as my invention is:

1. The combination with a bowl or other receptacle, of an open top auxiliary receptacle provided with a discharge lip overhanging said first-mentioned receptacle, and means for admitting hot and cold water into the lower portion of said auxiliary receptacle and controlling means operable 35 from the top thereof.

2. The combination with a bowl or receptacle, of an auxiliary receptacle in rear thereof, said receptacle having a well to meet the rim of the bowl with a discharge 40 lip overhanging the bowl, hot and cold water connections, valves controlling the same, a common discharge from said connections entering the lower portion of said auxiliary receptacle, and controlling means for said 45 valves passing upward through the auxiliary receptacle to be operable from the top thereof.

3. The combination with a bowl or other receptacle having an apertured rim portion, 50 of an auxiliary receptacle inserted in the aperture of the rim, and having an annular shoulder engaging the rim marginally of the aperture to support said receptacle, said receptacle further having a lip portion overhanging said bowl, a clamping member carried by the receptacle beneath said rim and

engaging the latter, and means for supplying water to the lower end of said auxiliary receptacle.

4. The combination with a bowl or other receptacle, of an open top auxiliary receptacle arranged to overflow into said bowl, a fitting laterally connected to said auxiliary receptacle and communicating with the lower portion thereof, hot and cold water pipes having discharge connection with said fitting, valves within said fitting respectively controlling the flow of hot and cold water, a stem arranged within said receptacle for the common control of said valves, and an operating handle carried by said stem.

5. The combination with a bowl or other receptacle, of an open top auxiliary receptacle arranged to overflow into said bowl, a fitting laterally connected to said auxiliary receptacle and communicating with the lower portion thereof, hot and cold water pipes respectively having discharge connection with said fittings, valves within said fitting respectively controlling the flow of hot and cold water, and a common means for controlling and proportioning said flow.

6. The combination with a bowl or other receptacle, of an open top auxiliary receptacle arranged to overflow into said bowl, a fitting laterally connected to said auxiliary receptacle, hot and cold water pipes having discharge connection with said fitting, slide valves within said fitting controlling the flow of hot and cold water, a vertical control stem for said valves, a handle carried by said stem, and cams upon said stem engageable with said valves to successively unseat the same.

7. The combination with a bowl or other receptacle, of an auxiliary receptacle removably secured to said bowl, a fitting connected to said auxiliary receptacle, hot and cold water pipes having discharge connections with said fitting, spring influenced slide valves within said fitting controlling the flow of hot and cold water whereby a mixture thereof may be discharged within said receptacle, a control stem for said valves disposed within said auxiliary receptacle and extending above the same, a handle carried by said stem, and spaced cams carried by said stem engageable with said valves to successively unseat the same.

In testimony whereof I affix my signature.

WILLIAM B. STRATTON.
